By Thomas G. Orwig, Attorney.

UNITED STATES PATENT OFFICE.

FRANK E. KNIGHT, OF GRINNELL, IOWA.

TRANSFORMABLE TRUNK.

SPECIFICATION forming part of Letters Patent No. 693,973, dated February 25, 1902.

Application filed December 27, 1900. Serial No. 41,219. (No model.)

To all whom it may concern:

Be it known that I, FRANK E. KNIGHT, a citizen of the United States, residing at Grinnell, in the county of Poweshiek and State of Iowa, have invented a new and useful Transformable Trunk, of which the following is a specification.

My object is to provide a portable trunk with a hinged cover that can be swung upward and reversed, so as to bring its rear portion to the front, and inverted and supported in an elevated position to be advantageously used as a desk for writing thereon, while the trunk and a movable tray in the trunk remain stationary.

My invention consists in the construction, arrangement, and combination of parts, as hereinafter set forth, pointed out in my claims, and illustrated in the accompanying drawings, in which—

Figure 1 is a transverse sectional view showing the trunk closed, and Fig. 2 is a corresponding view showing the hinged top portion of the trunk in an inverted and elevated position as required for practical use as a table or desk. Dotted lines indicate the position of the hinged top when it is simply swung upward and retained in a vertical position as required in opening the trunk to gain access thereto for moving the tray in and out and packing and unpacking. Fig. 3 is a detail view of a locking device adapted for retaining the hinged top in a vertical position, as indicated by the dotted lines in Fig. 2.

The letter A designates the bottom portion of a trunk that may vary in size as desired. The front A² is lower than the back B, and the mating ends C are inclined downward at their top edges and rear portions to the level of the top edge of the front A², as clearly shown in Fig. 1. The mating ends D of the hinged top are fitted to the mating ends C of the lower portion of the trunk, and fixed to the ends of the flat top F, that is hinged to the top edge of the fixed back B, and H is the front fixed to the mating ends C and the flat top F.

The top portion of the trunk is connected with the top of the back of the lower portion by means of duplex strap-hinges. The main part m of each has a hinged extension m' at one end fixed on the outside and rear portion

of the top F, and an elbow m'' at its other end adapted to overlie the corner, and to the end of the elbow is hinged another strap m''', adapted to be fixed to the outside of the back B in such a manner that the duplex hinges can assume position as shown in Fig. 2 to aid in maintaining the top in an elevated and inverted position. An additional hinged connection between the lower portion of the trunk and the hinged and invertible top portions consists in straight metal straps n and elbow-shaped straps n', being pivotally connected, and the ends of the straight straps n pivoted to the inside faces and front portions of the mating ends C of the bottom portion and the ends of the elbows n' to the rear and top corners of the mating ends D of the hinged upper portion in such a manner that they will fold into position as shown in Fig. 1 when the trunk is closed and extend upward and forward at an angle, as shown in Fig. 2. Cleats r, fixed to the inside faces of the ends C of the main portion of the trunk, support a removable tray s, that is placed on the cleats.

To retain the hinged top in a vertical position, as shown by dotted lines in Fig. 2, coinciding slots are formed in the top F and straps m to admit the passage of turn-buttons s, that are mounted on the inner ends of bearers s', fixed to the straps m in such a manner that they will allow the turn-buttons to pass outward into position, as shown in Fig. 2. When the hinged top is adjusted, as shown by dotted lines, the turn-buttons overlie the inside face of the top and lock the top F and the parts m and m' of the duplex hinges in parallel overlying position, as required to retain the top stationary in a vertical position.

It is obvious the trunk may be provided with a lock and covered with leather or other suitable material and finished in any known style of art. It is also obvious that the flat top F when in an inverted position, as shown in Fig. 2, will project forward relative to the stationary lower part of the trunk, so that a person seated at the side or front of the inverted and elevated top can extend his knees under it, as required to use the trunk conveniently and advantageously for the purposes of a desk.

Having described the construction, arrangement, and combination of the different parts,

the practical operation and utility of my invention will be understood by persons familiar with the art to which it pertains.

What I claim as new, and desire to secure 5 by Letters Patent therefor, is—

1. In a portable trunk a lower portion that is higher at its back than at the front, a top portion fitted on the top of the lower portion, duplex hinges composed of a central portion 10 that is elbow-shaped at one end and has extensions hinged to each end, and the extension at the elbow-shaped end fixed to the back of the lower portion of the trunk and the extension at the other end fixed on the front 15 portion of the top, to operate in the manner set forth, for the purposes stated.
2. In a portable trunk, a lower portion that is higher at its back than at the front, a top portion fitted on the top of the lower portion, 20 duplex hinges composed of a central portion that is elbow-shaped at one end and has extensions hinged to each end, and the extensions at the elbow-shaped end fixed to the back of the lower portion of the trunk and 25 the extensions at the other ends fixed on the front portion of the top, straight bars and elbow-shaped bars pivotally connected and the ends of the straight bars pivoted to the inside 30 faces and front portions of the mating ends of the lower part of the trunk and the elbow-

shaped parts pivoted to the upper rear portions of the same mating ends, to operate in the manner set forth, for the purposes stated.

3. In a portable trunk a lower portion that is higher at its back than at the front, a top 35 portion fitted on the top of the lower portion, duplex hinges composed of a central portion that is elbow-shaped at one end and has extensions hinged to each end and the extensions at the elbow-shaped ends fixed to the 40 back of the lower portion of the trunk and the extension at the other end fixed on the front portion of the top, straight bars and an elbow-shaped bar pivotally connected and the 45 ends of the straight bars pivoted to the inside faces and front portions of the mating ends of the lower part of the trunk and the elbow-shaped parts pivoted to the upper rear portions of the same mating ends, slots in the in- 50 veritable wooden top, coinciding slots in the overlying parts of the duplex strap-hinges, pins fixed to the central members of said hinges and turn-buttons on the ends of said pins, all arranged and combined to operate in the manner set forth, for the purposes stated. 55
